TEST CONTAINER DOLLY FOR MOVABLY
SUPPORTING TEST CONTAINERS, ETC.

Joseph C. Kotkowski, 6720 Duluth Ave.,
Baltimore, Md. 21222

Filed Jan. 21, 1970, Ser. No. 21,012

Term of patent 14 years

Int. Cl. D12—02

U.S. Cl. D14—3

FIG. 1 is a perspective view of a test container dolly for movably supporting test containers, etc. showing my new design, the sides opposite those shown are exactly alike;

FIG. 2 is a top plan view; and
FIG. 3 is a bottom view.

I claim:

The ornamental design of a test container dolly for movably supporting test containers, etc., as shown and described.
